[57] CLAIM

The ornamental design for a housing for a two-way radio communications device, as shown and described.

DESCRIPTION

FIG. 1 is an isometric view of a housing for a two-way radio communications device showing our new design; FIG. 2 is a front elevational view thereof; FIG. 3 is a left elevational view thereof; FIG. 4 is a right elevational view thereof; FIG. 5 is a top plan view thereof; and, FIG. 6 is a bottom plan view thereof. The rear is not considered to be a part of my claimed design.
